(57) **CLAIM**

The ornamental design for a luminous module of lights for vehicles as shown and described.

DESCRIPTION

FIG. 1 is a top, front and right side perspective view of a luminous module of lights for vehicles showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 3; and,

FIG. 11 is an enlarged view of portion 11 in FIG. 6.

The broken lines in the drawings illustrate portions of the luminous module of lights for vehicles which form no part of the claimed design.
